M. C. HUTTO

GRINDING DEVICE

Filed Sept. 10, 1923

UNITED STATES PATENT OFFICE.

MARDEN C. HUTTO, OF BRYAN, OHIO.

GRINDING DEVICE.

Application filed September 10, 1923. Serial No. 661,883.

This invention relates to lapping or grinding devices adapted for the grinding or finishing of substantially cylindrical apertures, and the object of the invention is to 5 provide a device for the purpose stated having a plurality of abrading members that are radially adjustable for operation on cylinders of different diameters within the capacity of the device and in which a control 10 element is utilized to fix the general limit of contraction in any of the adjusted positions of the abrasive members and free to move subject to the control arising through connection with the abrading members. It has 15 commonly been the practice heretofore to provide a series of radially adjustable abrading members and a control element to adjust the same but in the majority of instances within my knowledge the abrading members 20 of grinding and lapping devices are spring projected and thus may yield to inaccuracies of a cylinder wall being ground and consequently are not efficient in the truing of the cylinder wall as to straightness and uniformity of diameter from end to end. It is 25 further common practice to provide a positive backing for the blades of the reamers and similar tools but in all such cases the adjusting device is not subject to an automatic control or supported by the blades; in other 30 words, the adjusting means or control device in each tool is fixed in the adjusted position.

This invention seeks to obviate the difficulties arising in such previous structures by 35 the provision of an adjusting or control element for the abrading members that "floats" as a unit in the adjusted position and provides a positive backing for the abrading members in the grinding operation and by 40 reason of its "floating" relationship permits the abrading members to lie at an angle to the axis of the tool to fit a tapered wall within the limit permitted by the construction of the device. It is therefore an object of this 45 invention to provide a tool having a series of abrading members radially adjustable and extending parallel with the axis of the tool and a control element that "floats" on the longitudinal axis of the tool due to its being supported in position solely by engagement 50 with the portions provided therefor on the abrading members, the floating movement being subject to control by the abrading members. It is also an object of this invention to provide, in a tool of the character described, a pair of cone members with the

small ends in opposed relation and supported as a unit in the adjusted position by reason of engagement of the portions of the abrasive holders adjacent opposite ends respectively 60 with the respective cones.

These and other objects and the several features of the invention are hereinafter more fully described and claimed, and a tool embodying my invention is shown in the 65 accompanying drawings, in which—

Fig. 1 is an elevation of a lapping device embodying my invention.

Fig. 2 is a bottom view thereof.

Fig. 3 is an enlarged section taken on line 70 3—3 of Fig. 2.

Fig. 4 is a section taken on line 4—4 of Fig. 3.

Fig. 5 is a perspective view of one of the 75 retaining springs.

Fig. 6 is a section through an alternative type of lapping number.

As shown in Fig. 1 the device comprises a handle 1 mounted in a member 2 which is provided with a bifurcated lower end 3. A block 4 shown in Fig. 3 is secured in the bifurcated end 3 by means of the pin 5 which passes through a larger pin 6 extending through the block. The pin 6 is mounted at its outer ends in a pair of upwardly extending lugs 7 which are formed integrally with the head 8 of the device. The head 8 of the device is provided with a central longitudinal bore 9 therethrough and the three arcuate lapping members 10 are each provided with a pair of pins 11 molded therein, the embedded ends of the pins being provided with annular grooves 12 so as to be securely held in the soft lapping metal which is usually lead or a lead composition or alloy, the metal being preferably sufficiently soft to receive an abrasive. A pair 90 of conical members 13 and 14 are mounted in the central bore 9 and are movable together or apart by adjustment of the screw 95 15 as will be readily understood. The head 8 is provided with reamed radial apertures 16 for receiving the pins 11 and the ends of the pins are shaped to fit the conical members 13 or 14. The head 8 is provided with three flat faces 17 and a spring 18 is mounted on each flat face 17 by means of a screw 19, the ends of each spring 18 engaging in the notches 20 provided therefor in the pins 11, the shape of the spring being shown more 110 particularly in Fig. 5.

The device assembled as shown in Fig. 3

may be introduced into a cylindrical aperture of slightly larger diameter and by turning the screw the conical members 13 and 14 are drawn together which spread the lapping faces 10 apart to contact with the cylinder wall, the outward movement of the pins forcing the springs 18 outwardly as shown and the construction is such that the springs press the ends of the pins to engagement with the respective conical members 13 and 14 at all times. Previous to the lapping operation an abrasive compound may be applied to these faces 10. At this time the operator by grasping the handle 1 may move the device up and down and turn it around in the cylinder to correctly lap the cylinder walls, the handle being connected to the head 8 by a universal joint to allow the device to be easily operated from different angles without wearing the cylinder out of round or applying pressure unevenly. As will be seen in Figs. 1 and 3 the lapping faces are provided with apertures 21 therethrough to allow a screw driver to be inserted for loosening or tightening the screw 19 which holds the spring 18 in place. Each device is provided with several sets of lapping faces, each lapping face being provided with pins 11 the same as those shown in Fig. 3 so that by removing the spring 18 lapping faces of different diameters may be secured to the head and allow the device to be used with cylinders of greatly varying diameters.

An alternative form of lapping member 35 may be used as shown in Fig. 6 comprising a base 30 formed of a metal which may be die cast. A grinding stone 32 and a pair of pins 11 are positioned in the die and the metal is cast thereabout to securely embed 40 the stone 32 and pins 11 therein. The stone 32 may also be fixed in a metal shell by use of lead or other adaptable metal 33 between the stone 32 and the flange 31 of the retaining case which also may be considered as 45 a form suggested by Fig. 6. Due to the rounded faces of the stones being narrow the stones do not have to be changed for lapping different sized cylinders as is the case with the arcuate lapping members shown in 50 Figs. 3 and 4. The adjustment of the device is the same with either type of lapping members as will be readily understood and the lapping device when used with the stone lapping members provides a universal lapping device for lapping all cylinders within the 55 adjustment of the mechanism.

It will be evident from the foregoing description that the control element, namely, the cones and adjusting screw "float" as a 60 unit with the cones in an adjustably fixed or rigid relation on the longitudinal axis of the tool subject to control by reason of contact of the cones with the respective pins of the abrading members and, due to the general relationship of parts and the usual clear-

ances in the fitting of the parts, the cones may assume a position causing the abrasive devices at one end to be moved outwardly and the abrasive members at the opposite end to be moved inwardly to a like extent. This is due to the fact that the cones are both of the same taper and thus, to the extent permitted by the construction of the tool, the stones may assume an angle to the axis of the tool to fit a tapered cylinder wall having a taper not greater than the permissible taper of the abrasive members.

Preferably the angle of the cone faces relative to the axis of the tool is small, usually not greater than about fifteen degrees, although it may be varied somewhat without materially affecting the operation of the tool but an essential characteristic of the construction shown is that the control element floats as a unit subject to control of the contacting pins of the lapping members 10 shown in Fig. 3 or of the abrasive holder as shown in Fig. 6 as these provide the sole support of the adjusting device or control element in the head.

Preferably also these cone members are formed with a cylindrical portion which fits the bore 9 of the head and thus the cone members are positively supported against lateral movement by pressure exerted thereon by the abrasive members.

Having thus fully described my invention, its utility and mode of operation, what I claim and desire to secure by Letters Patent of the United States is—

1. In a grinding device, a head having a longitudinal bore, a series of abrasive members carried by the head and movable radially relative thereto, said head having a series of apertures opening to the longitudinal bore, pins on the said abrasive devices extending through the said apertures, cone members having the small ends in opposed spaced relation in the said longitudinal bore, said pins of the abrasive devices engaging the respective cones, yieldable means maintaining the pins in contact with the cones, the said cones positively determining the limit of contraction of the abrasive devices, and means for varying the distance apart of the cones, the said cones being freely movable as a unit in their adjusted relation.

2. In a grinding device, a head having a central longitudinal bore, a pair of cones in opposed spaced relation freely slidably in and fitting the bore, abrasive devices having portions engaging the respective cones, means for varying the distance apart of the cones which maintains positively that adjustment of the cones which determines the limit of contraction of the abrasive devices, the said cones being freely movable as a unit in the adjusted relation, and spring means for contracting the abrasive devices

to maintain the said portions thereof in contact with the cones.

3. In a grinding device, a head having a central longitudinal bore, a pair of cones having the small ends thereof in opposed relation and freely slideable in and fitting the bore, a rod on which the said cones are mounted, one of the said cones being threaded on the rod and the other cone slideable thereon whereby turning the rod varies the spacing of the cones, a spring tending to maintain the cones in the determined spaced relation, said cones, rod and spring being freely movable as a unit in the bore, abrasive devices having portions fitting the respective cones, and spring means for contracting the abrasive devices to maintain the said portions in contact with the cones, said cones providing a means positively determining the limit of contraction of the abrasive devices.

4. In a grinding tool for operation on members having cylindrical apertures, the combination of a head, a plurality of abrading members having abrading surfaces and radially adjustable in said head, and a control element having parts adjustably rigid relative to each other to positively fix the general limit of contraction of the abrading surfaces, but free when in operation to move longitudinally of the body in either direction as a unit subject to control by the abrading members.

5. In a grinding tool for use on members having cylindrical apertures, the combination of a head, one or more abrading members having abrading surfaces and radially movable in respect to said head, and a control element cooperating with said abrading members and having parts adjustably rigid relative to each other to positively fix the general limit of contraction of the abrading surfaces, said control element arranged however to automatically allow and control a limited tilting movement of the abrading members end for end in setting the abrading members up against cylinder walls non-parallel to the axis of the tool.

6. In a grinding tool for use on members having cylindrical apertures, the combination of a head, one or more abrading members having abrading surfaces and radially guided, and a control element cooperating with said abrading members and having parts adjustably rigid relative to each other to positively fix the general limit of contraction, said control element arranged however to automatically allow and control a limited

tilting of the abrading members end for end in setting the abrading members up against cylinder walls non-parallel to the axis of the tool, and to allow and cause the abrading member to automatically assume a parallel position as the cylinder walls are ground toward a parallel condition with respect to the axis of the tool.

7. In a device for grinding cylindrical apertures, a head, a series of abrasive members extending longitudinally thereof, adjusting means common to said members, adjustable at will and adapted to act through opposite ends thereof to cause the abrasive members to engage a surface under pressure, at an angle to the axis of the tool, said means being then still self-adjusting to cause the faces of the abrasive members to gradually assume a position parallel with the axis of the tool as pressure becomes released, said adjusting means providing a positive backing for the abrasive members in any of the operative adjusted or self-adjusted positions until they are freed by the grinding operation.

8. In a lapping device, a head having a longitudinal bore, a series of abrading members carried by the head and radially movable therein, cone members having the small ends thereof in opposed relation slideable in the said bore, means for varying the distance apart of the cone members, and maintaining the same relatively rigid, said abrading members each having parts connected therewith and engaging the respective cones and providing the sole means of support of the cone members in the bore.

9. In a grinding device, a head having a central longitudinal bore, a pair of cones in opposed spaced relation in the said bore, means for varying the distance apart of the cones, and maintaining the same relatively rigid, a series of abrading devices extending longitudinally of the head each provided with means adjacent each end thereof engaging the respective cones whereby the varying of the distance apart of the cones varies the distance of the faces of the abrading devices from the axis of the said bore, and yieldable means tending to maintain the abrading devices with the said parts in engagement with the respective cones, the said cones being movable as a unit in the adjusted relation in the said bore subject to control by the abrading members.

In testimony whereof, I sign this specification.

MARSDEN C. HUTTO.
